UNITED STATES PATENT OFFICE.

EDWARD B. HESS, OF ORLANDO, FLORIDA, ASSIGNOR TO ROYAL TYPEWRITER COMPANY, INC., OF NEW YORK, N. Y., A CORPORATION OF NEW YORK.

TYPEWRITING MACHINE.

Application filed June 18, 1926. Serial No. 116,872.

This invention relates to a new and useful paper table which is mounted to swing forwardly from its operative position and when so moved a scale on the rear side of said table is brought into position adjacent the margin stop bar to permit easy setting of the margin stops to any desired location. Means is provided for limiting the movement of the paper table in either direction about its pivot.

The invention is shown as embodied in a Royal portable machine and is especially adapted for small machines of compact construction, where considerations of space are important. It may, however, be embodied in other types of machines without in any way departing from the scope of the invention.

In the drawings:

Figure 1 is a fore and aft section through the carriage of the machine embodying the invention, with parts shown in elevation.

Figure 2 is a similar view with the paper table swung to its forward inoperative position.

Figure 3 is a plan view of the paper table detached.

Figure 4 is a similar plan view of the upper edge portion of the paper apron or paper pan to which the paper table is hinged.

Figure 5 is a top plan view of the carriage with the paper table swung to its forward position and showing the relation of the scale to the margin stops at this time.

Figure 6 is an elevation of a portion of the paper table and paper apron, showing the spring for holding the parts in rearward position.

Figure 7 is a rear view of a portion of the paper table and paper apron, showing the position occupied by the scale when the paper table is in operative position.

The drawings disclose a conventional carriage A in which is mounted a platen B against which bear front feed rolls C and rear feed rolls D. A paper apron or pan E of any old or desired type which extends partway about the platen and terminates at its rear in approximately the horizontal plane of the top of the platen. A pivot rod F mounted in the carriage carries the

side arms F' of the usual roll-holding bail which carries feed rolls G. There is also shown a margin stop bar H and margin stops K carried thereby. These parts as above stated are similar to those employed in the Royal portable machine, but may be of different construction without affecting the invention.

The paper table 1 having an upper rolled edge is hinged to the upper edge of the paper apron E somewhat after the form of a piano hinge. As shown in Figures 3 and 4, the lower edge of the paper table is provided with the projecting portions 2 separated by cut outs, while the upper edge of the paper apron is provided with similar projections 3, which engage the cut outs in the paper table. A hinged rod 4 passes through eyes formed by rolling the edges of the projections 2 and 3. A scale member 5 having the usual gradations 6 is fastened to the rear side of the paper table adjacent the lower edge thereof in such manner that when the paper table is in its operative position the numerals on the scale are upside down. This scale may be fastened to the paper table in any desired manner. One or more of the sections 3 of the hinge may have a rearwardly projecting part 7 with which the lower edge of the paper table 1 contacts 75 when the parts are in the normal or Figure 1 position to limit the rearward movement of the table. The forward movement of the table to the Figure 2 position is limited by the upper edge of the table contacting with 80 the paper rolls G.

In the front and lower portion of the paper table is a depression 8 and adjacent thereto in the upper edge of the paper apron is a similar depression 9. The end of the depression 8 is provided with an opening 10 extending through the paper table and the end of the depression 9 is provided with a similar opening extending through the paper apron. A spring 12 is coiled about a hinge 4 and one end lies in the depression 8 and passes through the hole 10. The other end of the spring lies in the depression 9 and passes through the hole 11. This leaves 85 the upper surface of the paper table and 100

paper apron smooth and prevents the spring from interfering in any way with the ready movement of the paper thereover.

It will be noted from the drawings that the margin stops lie immediately behind the paper table and adjacent thereto and that when the parts are in the normal or Figure 1 position, the stops cannot be adjusted readily to any desired position. When the paper table is swung forward to the Figure 2 position, it will bring the scale to the position shown in Figure 5. This scale will lie immediately adjacent the margin stops with their index lines 12 which can be adjusted readily to any desired position with reference to this scale. This enables a very compact construction to be employed and at the same time permits the operator to adjust the stops as desired to any desired position without difficulty. When the paper table is released the spring 12 will return the same to normal position without further attention.

It is obvious that the invention may be embodied in widely different types of machines and that the details of construction can be changed in many ways without in any degree departing from the spirit of the invention. The precise form of hinge, the particular location of the spring, and other features of this character may be modified. It is, therefore, to be understood that the invention is to be regarded as limited only by the scope of the appended claims.

33 I claim:

1. In a typewriting machine, the combination of a margin stop bar, stops adjustable thereon, a paper table lying in front of and close to said stop bar, a scale on the rear side of said table adjacent said stops, and a mounting for said paper table permitting its movement forwardly to bring said scale into view and expose said stops for ready adjustment from the front of the machine.
2. In a typewriting machine, the combination of a margin stop bar, stops adjustable thereon, a paper table lying in front of and close to said stop bar, a scale at the rear lower edge of the paper table adjacent said stops, and a pivotal mounting for said paper table permitting its movement forwardly to bring the scale into view and expose the stops for ready adjustment from the front of the machine.
3. In a typewriting machine, the combination of a margin stop bar, stops adjustable thereon, a paper table lying in front of and close to said stop bar, an inverted scale at the rear lower edge of the paper table adjacent said stops, and a mounting for the paper table which permits it to be moved to a position which brings the scale to correct reading position and exposes the stops for ready adjustment from the front of the machine.
4. In a typewriting machine, the combina-

tion of a carriage, a platen thereon, a roll holding bail having pressure rolls which engage the platen near the top thereof, and a paper table mounted to swing forward from operative position to a position in which the upper end engages the rolls carried by said bail.

5. In a typewriting machine, the combination of a carriage, a platen thereon, a roll holding bail having pressure rolls which engage the platen near the top thereof, a paper table mounted to swing forward from operative position to a position in which the upper end engages the rolls carried by said bail, and means for limiting the rearward movement of said table.

6. In a typewriting machine, the combination of a platen carriage, a paper apron carried thereby, a paper table pivoted to the upper edge of the paper apron and movable forwardly from its operative position, a scale carried by the rear side of said paper table and brought into position of use by said forward movement of the table, means for moving said table to its operative position, and means for limiting the movement of the table in either direction.

7. In a typewriting machine, the combination of a margin stop bar, stops adjustable thereon, a scale separate from but closely adjacent said stop bar, a paper table lying in front of and close to said stop bar, and a mounting for said table permitting its movement forwardly to expose said stops for ready adjustment from the front of the machine with direct reference to said scale.

8. In a typewriting machine, the combination of a margin stop bar, stops adjacent thereto, a scale separate from but closely adjacent said stop bar, a paper table lying in front of and close to said stop bar, a mounting for said table permitting its movement forwardly to expose said stops for ready adjustment from the front of the machine with direct reference to said scale, means tending to move the table to its operative position, and means for limiting the movement of the table in either direction.

9. In a typewriting machine, the combination of a platen carriage, a paper apron carried thereby, a paper table pivoted to the upper edge of the paper apron and movable forwardly from its operative position, a margin stop bar located immediately behind the paper table and apron and closely adjacent thereto, a stop carried by said bar, and a movable scale located adjacent said stop bar, the forward movement of the paper table exposing the stop bar and bringing the scale into such position that the stop may be adjusted by direct reference thereto.

10. In a typewriting machine, the combination of a platen carriage, a paper apron carried thereby, a paper table pivoted to the upper edge of the paper apron and movable

forwardly from its operative position, a margin stop bar located immediately behind the paper table and apron and closely adjacent thereto, a stop carried by said bar, a movable scale located adjacent said stop bar, the forward movement of the paper table exposing the stop bar and bringing the scale into such position that the stop may be ad- justed by direct reference thereto, means for moving said table to its operative position **10** and means for limiting the movement of the table in either direction.

In testimony whereof, I have hereunto subscribed my name.

EDWARD B. HESS.
